US00D842015S

(12) **United States Design Patent** (10) Patent No.: **US D842,015 S**
Strempe et al. (45) Date of Patent: ** Mar. 5, 2019

(54) **MOBILE AND COLLAPSIBLE WORKBENCH**

(71) Applicant: **Kreg Enterprises, Inc.**, Huxley, IA (US)

(72) Inventors: **Shelby Lee Strempe**, Huxley, IA (US); **Frederick James Good**, Ogden, IA (US)

(73) Assignee: **KREG ENTERPRISES, INC.**, Huxley, IA (US)

(**) Term: **15 Years**

(21) Appl. No.: **29/584,702**

(22) Filed: **Nov. 16, 2016**

(51) LOC (11) Cl. **06-03**

(52) U.S. Cl.

USPC **D6/684**

CLAIM

The ornamental design for a mobile and collapsible workbench, as shown and described.

DESCRIPTION

FIG. 1 is a perspective view of a mobile and collapsible workbench, shown in an open state;
FIG. 2 is a front elevation view of thereof;
FIG. 3 is a rear elevation view of thereof;
FIG. 4 is a left side elevation view thereof;
FIG. 5 is a right side elevation view thereof;
FIG. 6 is a top elevation view thereof;
FIG. 7 is a bottom elevation view thereof;
FIG. 8 is a perspective view of the mobile and collapsible workbench, shown in a collapsed state;
FIG. 9 is a front elevation view thereof,
FIG. 10 is a rear elevation view thereof;
FIG. 11 is a left side elevation view thereof;
FIG. 12 is a right side elevation view thereof;
FIG. 13 is a top elevation view thereof; and,
FIG. 14 is a bottom elevation view thereof.
A mobile and collapsible workbench. The broken lines depict portions of the article that form no part of the claimed design.
